UNITED STATES PATENT OFFICE.

DANIEL B. SWEENEY, OF MIDDLETOWN, NEW YORK.

DESIGN FOR A BOTTLE.

Application filed September 11, 1922. Serial No. 3,691. Term of patent 14 years.

To all whom it may concern:

Be it known that I, DANIEL B. SWEENEY, a citizen of the United States, residing at Middletown, in the county of Orange and State of New York, have invented a new, original, and ornamental Design for a Bottle, of which the following is a specification, reference being had to the accompanying drawing, forming part thereof.

The figure is a plan view of a bottle, showing my new design.

I claim:

The ornamental design for a bottle, as shown.

DANIEL B. SWEENEY.
